UNITED STATES PATENT OFFICE.

JOSEPH ATWOOD AND GUSTAV ESCHER, OF WASHINGTON, DISTRICT OF COLUMBIA.

STEAM-GENERATING APPARATUS.

No. 895,938.

Specification of Letters Patent. Patented Aug. 11, 1908.

Application filed September 23, 1907. Serial No. 394,125.

To all whom it may concern:

Be it known that we, JOSEPH ATWOOD and GUSTAV ESCHER, citizens of the United States, and residents of Washington, in the District of Columbia, have invented an Improvement in Steam-Generating Apparatus, of which the following is a specification.

This invention is an improvement in steam heating apparatus, and particularly in the means for generating the steam; and the invention consists in certain novel constructions and combinations of parts as will be hereinafter described and claimed.

In the drawing, Figure 1 is a sectional elevation of an apparatus embodying the invention. Fig. 2 is a detail view illustrating the regulating device for controlling the passage of gas to the burners. Fig. 3 is a detail view illustrating the damper controlling the passage of air to the forced draft pipe; and Fig. 4 is a vertical section.

In carrying out the invention, we employ a pair of boiler sections A spaced apart, arranged preferably in axial alinement, and connected by upper and lower pipes B and C, which open at their opposite ends into the boiler sections A, and form connections between the same. A pipe B' leads upward from the pipe B, and forms a feed pipe furnishing the supply of steam to the radiators, not shown, and the pipe C is provided on opposite sides of its center with depending pipes C', forming water legs in connection with the lower pipe C, as shown. The pipe B' connects with the pipe B, through a suitable coupling, and the water legs C' connect with the pipe C through suitable couplings as shown. Flue tubes D open at their lower ends at the lower ends of the legs C', and extend upwardly therein and thence bend laterally outward through the tube C, and extend thence longitudinally within the boiler sections A, are bent upwardly at D' near the outer ends of the boiler sections A, and returned within the boiler sections and extend at D² out through the inner end plates of the boiler sections A, and connect at their adjacent ends by means of suitable couplings with a forced draft pipe E, which may discharge at its upper end to the air or to any suitable connection with a chimney, and is provided at its middle at its lower end with an air inlet pipe F, having a damper F', controlling the amount of air supplied.

Manifestly, suitable packing is provided where the pipes B and C connect with the

boiler sections, and where the return portions of the flue tubes D pass through the inner end plates of the boiler sections, as well as where the flue tubes D connect with the lower ends of the water legs C', and this packing may be effected in the manner shown in the drawing, or in any suitable manner, as will be understood by those skilled in the art.

Burners G, which may be of the Bunsen type, are mounted on a gas pipe G', supplied through a feed pipe H, having a valve H', the supply pipe I connecting with the pipe H through a cylinder J having outlet openings J' and J², the latter being preferably arranged in a series as shown. A plunger K operates in the cylinder J, and is connected with the rod L' of a piston L operating in a cylinder M, and exposed to the pressure of the steam by means of a pipe M' connecting it with the pipe B', the latter also having a steam gage N suitably connected with it to indicate the pressure. The cylinder M has a blow-off or exhaust port M², and the steam actuated piston L operates to regulate the amount of gas supplied to the burners in proportion to the steam pressure, the latter as it increases reducing the supply of fuel, and thus reducing the steam generated, as will be understood from the drawing.

It will be noticed that we provide the boiler in sections with hot air flues receiving the heat directly from the burners and extending up through water legs, and thence laterally through tubes connecting the boiler sections, and circulating within the boiler sections, and thence passing out between the same.

A float O in one of the boiler sections A, operates through a suitable valve to control the feed of water to the boiler, and maintain the water line at the desired level.

In the construction shown, we provide a bracket P supporting the gas pipe G', from the pipe C, and we also provide brackets Q and R, the former supporting the gas supply pipe above the cylinder J, and the latter forming a support for a weight carrying lever R' which operates upon the rod L' of the piston L, as shown in Fig. 1 of the drawing.

It should be understood that our invention is especially designed for use with gas and for suspending from the ceiling of a room, the generating apparatus being comparatively small, and it being desirable to utilize the steam generated in two opposite boilers in order to supply the volume of steam necessary for the heating apparatus and in sus-

2

pending the two boilers in order to avoid any racking or straining of the joints, we find it desirable to connect the boilers above and below a central point so that the lower connecting pipe C will brace the boiler sections apart at their lower ends and the upper pipe B will brace them apart at their upper ends so that the weight of the water in the two boilers and of the boilers themselves will be borne in such a manner as to relieve the racking and straining before referred to. Also in utilizing the heat of the gas and in applying such heat to the boilers I find it convenient to provide a connecting pipe with the depending water legs as best shown in Fig. 1 to facilitate the application of the heat in a simple and efficient manner.

We claim:

1. An apparatus substantially as described, comprising a pair of boiler sections spaced apart, upper and lower pipes connecting said sections and establishing communication between the same, a supply pipe leading from the upper connecting pipe, a pair of pipes depending from the lower connecting pipe and forming water legs, flue tubes connecting with the lower ends of the water legs and extending upwardly therein and thence extending outwardly within the lower connecting tubes, and longitudinally within the boiler sections, and returned within the boiler sections, and extending out through the inner end plates thereof, a draft pipe to which the upper ends of the flue tubes are connected, said draft pipe having an air vent provided with regulating means, burners below the flue tubes, and a gas pipe supplying fuel to said burners, substantially as set forth.
2. The combination in an apparatus substantially as described, of boiler sections spaced apart, upper and lower pipe connections extending between and establishing communication between the said sections, the lower connecting pipe having depending pipes forming water legs, flue tubes extending upwardly through said water legs and thence laterally through the connecting pipes into the boiler sections, and circulating within the latter, and extending out of the boiler sections, substantially as and for the purposes set forth.
3. The combination with a boiler section having a pipe in communication therewith said pipe being provided with a depending water leg, of an air flue extending upwardly within said water leg and thence through the connecting pipe into the boiler section and

circulated within the latter, and extending out of the boiler section to discharge at the outside thereof, substantially as set forth.

4. The combination with opposite boiler sections, of a water pipe connecting and establishing communication between said sections and having depending pipes forming water legs, flue tubes extending upwardly within the water legs and thence laterally within the connecting pipe into their respective boiler sections, and circulated within the latter and extending out of their boiler sections, and a draft pipe to which the upper ends of the flue tubes are connected, substantially as set forth.

5. In an apparatus substantially as described, the combination with a pair of boiler sections spaced apart, a pipe connecting and establishing communication between the sections and provided with depending pipes forming water legs, flue tubes extending upwardly in said water legs and thence laterally within the connecting pipes into their respective boiler sections, and circulated within the latter, and thence extending out of their boiler sections and connecting with a common discharge pipe, substantially as set forth.

6. The combination of opposite boiler sections spaced apart, a pipe connecting and establishing communication between said boiler sections, and having depending pipes forming water legs, flue tubes extending upwardly within their respective water legs, thence laterally outward through the connecting pipe into their respective boiler sections and circulating within the latter, and extending out of their respective boiler sections, substantially as set forth.

7. An apparatus substantially as described, comprising a pair of boiler sections spaced apart, upper and lower tubes connecting said sections and pressing the same apart above and below an intermediate point, a supply pipe leading from the upper connecting pipe and adapted to support the apparatus, flue tubes connected with the lower connecting pipe and open at one end to receive the heat and disposed thence within their respective boiler sections, and extending at the other ends out of the said boiler sections substantially as and for the purposes set forth.
